UNITED STATES PATENT OFFICE

2,560,817

MOTOR CONTROL SYSTEM FOR
DEODORIZING DEVICES

Charles F. Pfeifer, El Monte, Calif., assignor, by decree of court, to Nicholas H. Pfeifer, Anne Stinson, Sally Bateman, Marion Vincent, and Imogene Ross

Application May 7, 1949, Serial No. 91,935

3 Claims. (Cl. 318—484)

1

This invention relates to a novel device for removing unpleasant odors from toilets and other such enclosed areas.

An object of the present invention is to provide novel means for drawing air from a room, cleaning or deodorizing the same, and re-circulating it back to said room.

Another object of the invention is to provide air deodorizing means that can be switched on and left to complete its cycle of operation for a predetermined time period without the need for switching the same off.

A further object of the invention is to provide means, as indicated, that can, optionally, be placed in continuous operation.

A still further object of the invention is to provide novel switch-operated means, in a device of the character referred to, that requires only finger touch pressure on a starter button to institute the cycle of operation of said device.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a front elevational view showing the present device as installed in a wall of the room being served by said device.

Fig. 2 is a side elevational view thereof, a portion of the wall being in section.

Fig. 3 is a vertical sectional view as taken on line 3—3 of Fig. 1.

Fig. 4 is an electrical wiring diagram of the instrumentalities of said device.

While shown as a wall-installed unit, the present device may be constructed as a portable unit that can be connected to an electric outlet in any room or area the air of which requires cleaning or deodorizing. It will be seen from the following description that the device is adapted for use as an air conditioning unit since the same circulates the air of a room whether or not deodorant is employed therein.

The illustrated device comprises, generally, a front panel 10 that supports a base 11, an air-

2

circulating unit 12, a motor 13 for driving said unit, a double-pole-double-throw switch 14, cycle-timing means embodying an electrically operated timer 15 and a mercury switch 16 controlled thereby, a push button switch 17 for instituting the operation of the cycle-timing means, and suitable tell-tales 18 and 19 advising whether said device is in circuit for continuous operation or for periodic operation as controlled by switches 14 and 17.

According to the invention, the air-circulating unit comprises a fan or blower 20 that is provided with an air inlet 21 which preferably extends through panel 10 to be accessible from the room side of the device. Inlet 21 is shown as an upwardly angularly directed tube or pipe that is adapted to hold a quantity of material such as deodorant crystals 22. A suitable screen across the inlet to the blower 20 prevents the crystals from entering the blower housing. Access to tube 21 is afforded through a closure cap 23 that is provided with a foraminous face 24 offering minimum interference to air intake. Said cap may be hinged, as shown.

25 A variation of the inlet 21 may comprise a branched arrangement—one branch only containing crystals. A suitable valve is provided for effecting selection of which branch is open to the blower.

The motor is preferably of the air cooled type, 30 since, under certain conditions, the same may be in continuous operation. Accordingly, a fan 25 is provided to cool the same.

Switch 14 is indicated as a toggle switch 35 adapted to have one of two positions. The timer 15 is a unit comprising a low-geared motor having suitable reduction gearing providing for a slow speed of rotation of its output shaft 26. On said shaft is mounted a disc 27 in the periphery of which is formed a single V-shaped notch 28.

40 A pivoted arm 29 has a dog end 30 normally residing in said notch, the arm being generally horizontal until rotation of disc 27 causes the walls of the notch to displace the dog end 30 upwardly and thereby tilt said arm. The mercury switch 16 is carried by the arm, is open 45 when the arm is horizontal, and closed when tilted upon tilting of the arm.

Switch 17 is of the two point make type and 50 always seeks an open position. A binding post 31 is provided so that the wiring of the electric circuit for the above-named instrumentalities is simplified. Said circuit will be described in detail in the course of the following description of the operation of the device.

With switch 14 thrown to contact terminals

32 and 33 thereof, current will flow from line wire 34, through motor 13 and its circuit wires 35 and 36 to the opposite line wire 37. Simultaneously, tell-tale 18 will be illuminated by a circuit comprising lines 34, 38, 39, 40 and 37. Thus, the motor will be in continuous operation and tell-tale 18 lit apprising of the same.

With switch 14 thrown to contact terminal 41, the circuit through motor 13 is closed only to binding post 31, said circuit comprising lines 34, 35 and 42. The circuits through the timer 15 and through tell-tale 19 to said binding post are independent of switch 14. The timer circuit comprises lines 34 and 43, and the tell-tale lamp circuit comprises lines 34 and 44.

When switch 17 is pressed, the circuits through motor 13, timer 15 and tell-tale 19 are closed by connecting binding post 31 with lines 40 and 37. The motor will start and tell-tale 19 will light up. Simultaneously, timer 15 will start up instituting rotation of disc 27 and effecting tilting and, thereby, closing of mercury switch 16. Now, push-button switch 17 may be released since the mentioned circuits are maintained through the mercury switch from binding post 31, through lines 45, 46 and 37. The dog end 30 of arm 29 will ride the periphery of disc 27, holding switch 16 closed. When said dog end again falls into notch 28, said switch 16 will automatically open and, thereby, open the circuits through the motor, timer and tell-tale 19.

It will be seen that a person need only press and immediately release push-button 17 to institute the cycle of operation, and may leave the room which is served by the device, with assurance that, after a prescribed period, the operation will shut off.

The blower 12, of course, is provided with an outlet 47 and panel 10 with louvres 48 aligned with said outlet for returning the deodorized air from the room or area from which the same is drawn by the blower.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described the invention, what is claimed and desired to be secured by Letters Patent is:

1. A device of the character described, comprising a motor-driven air-circulating unit, a double-throw switch having a switch arm and two poles selectively engaged with said arm, an electric circuit to connect the motor of said unit for continuous operation and including said switch arm and one pole of the switch, a timing device, a normally open tiltable mercury switch, an operative mechanical connection between the timing device and said mercury switch to tilt the latter during operation of the former, a normally open push-button switch, a second electric circuit connecting the motor in series with the mercury switch and including said switch arm and the other pole of the double-throw switch, a circuit connecting the timer across the motor,

and a circuit connecting the push-button switch across the mercury switch, whereby, upon connection of said switch arm and said other pole and momentary closing of the push-button switch, both the motor and timer circuits are closed through the latter switch to institute simultaneous operation of the motor and timer, and whereby the mentioned mechanical connection is operated by the timer to tilt and close the mercury switch to maintain the operation of the motor and timer through the closed mercury switch after the push-button switch is released to open.

2. A device of the character described, comprising a motor-driven air-moving device, a double-pole double-throw switch, an electric circuit to connect the motor of said device for continuous operation and including one pole of said switch, a timing device, a tiltable switch normally open in one position and closed when tilted, an operative mechanical connection between the timing device and said tiltable switch to tilt the latter during operation of the former, a normally open push-button switch, a second electric circuit connecting said motor in series with the tiltable switch and including the other pole of the double-pole switch, a circuit connecting the timer across the motor, and a circuit connecting the push-button switch across the tiltable switch, whereby, upon closing of the second-mentioned pole of the double-pole switch and momentary closing of the push-button switch, both the motor and timer circuits are closed through the latter switch to institute simultaneous operation of the motor and timer, and whereby the mentioned mechanical connection is operated by the timer to tilt and, thereby, close the tiltable switch to maintain the operation of the motor and timer through the closed tiltable switch after the push-button switch is released to open.

3. A device according to claim 2: the mentioned mechanical connection comprising a disc driven by the timer and having a peripheral notch, and a pivoted arm mounting the tiltable switch and having an end riding the periphery of said disc to hold the tiltable switch closed and entering said notch to release the pivoted arm to move and, thereby, move the switch thereon to open.
